United States Patent Office

Des. 202,237
Patented Sept. 7, 1965

202,237

BOAT

Robert A. Wolfe, 435 Elizabeth Ave., Newark, N.J.

Filed June 30, 1964, Ser. No. 80,645

Term of patent 14 years

(Cl. D71—1)

FIG. 1

FIG. 2

FIG. 3

FIG. 4

FIG. 1 is a perspective view of the boat looking down into the forward portion of the cockpit, showing my new design;

FIG. 2 is a perspective view of the boat looking down into the rearward portion of the cockpit;

FIG. 3 is a perspective view, showing the rear portion of the under surface of the boat; and

FIG. 4 is a perspective view from the side of the boat, showing the forward portion of the boat's under surface.

I claim:

The ornamental design for a boat, as shown and described.
